UNITED STATES PATENT OFFICE.

JAMES S. RAY, OF DULUTH, MINNESOTA.

TIME-LOCK.

1,352,694.

Specification of Letters Patent. Patented Sept. 14, 1920.

Application filed March 21, 1919. Serial No. 284,120.

To all whom it may concern:

Be it known that I, JAMES S. RAY, a citizen of the United States, residing at Duluth, in the county of St. Louis and State of Minnesota, have invented certain new and useful Improvements in Time-Locks, of which I do hereby declare the following to be a specification.

My invention relates to time locks for doors and has for its object the provision of a simple time lock which may be conveniently used on store doors or other common doors. It also has for an object the automatic recording of the time that it is opened.

In the drawings, Figure 1 is a side elevation of said invention in locked position, partly in vertical longitudinal section approximately on the line A—B of Fig. 2. Fig. 2, is a horizontal section of said invention approximately on the line C—D of Fig. 3. Fig. 3, is a side elevation of said invention, corresponding to Fig. 1. Fig. 4, is a fragmentary side elevation of the hereinabove described hold back latch and means for operating and retracting the same.

In the drawings 1 is a lock case of any suitable structure preferably divided by a partition 1^a so as to provide a bolt chamber 1^b and a clock chamber 1^c. In one form of my invention the bolt chamber is adapted to contain the bolt 2 provided with guide rods 3 and 4 which rods extend through a partition or plate 5. Forward of said partition plate are positioned springs 6 of any suitable structure adapted to react against the forward face of said partition plate and the rearward, or inner end of said bolt.

Said clock chamber contains a clock of any suitable structure including a main spring 7 winding stem 7^a, an hour stem 8 and any suitable transmission mechanism adapted to be driven by said spring and to drive said hour stem, as the gears and pinions 9, 10, 11, 12, 13, 14 and 15 and spider spring 15^a. Said clock also includes a dial plate 16 and support plate 17, both mounted on said hour stem and adapted to turn therewith. Said plates may be of any suitable material, but said support plate is preferably of metal and said dial plate is preferably of white celluloid. If desired said dial plate and said support plate may be of the same material and constructed as a single plate or unit. A stationary plate 18 is also provided in said clock to support

said transmission mechanism and for the usual purposes of similarly disposed plates as well known to the art.

Said partition 1^a has a passage 1^d formed therethrough forward of said stationary plate 18 which passage is normally covered by a drop gate 19 mounted in guides 20 extending from said partition 1^a which drop gate is adapted to move upwardly, in an arc eccentric to said support plate, to open position. Extending from said drop gate and through said passage 1^d is a finger 19^a adapted to be engaged by a post 21 extending from said support plate 17 by means of which post and finger said gate is lifted for a short period once during each rotation of the support plate 17. Since the gate rises in an arc eccentric to said support plate, said finger will finally be drawn out of engagement with said post, whereupon the gate will drop. The free end of said rod 4 is adapted to extend so close to said gate when the gate is closed that the bolt 2 cannot be retracted far enough to unlock the lock, or door upon which it is mounted, since a very short retraction of the bolt will bring the end of the rod 4 into contact with the obstructing gate.

In the form shown, that portion of the rod 3 which extends forward of the plate 5 is positioned above the rod 4, but in rear of said plate 5 the free end of the rod 3 is bent downwardly and outwardly and rearwardly so that it lies in the same horizontal plane as said rod 4. Pivotaly secured to the free or rearward end of said rod 3, is a finger 3^a provided with a marker of any suitable nature such as a pencil 3^b. Said finger is adapted, when said bolt 2 and rod 3 are retracted, to extend through an opening 1^e in said partition 1^a and said marker is adapted to mark said dial near its periphery. Said dial preferably has a shallow bead or roll formed thereon at or near its periphery, over which said pencil is adapted to ride, thus insuring the clear marking of the dial thereby. Said finger 3^a is limited in its pivotal movement in one direction by a spring 3^c and in the opposite direction by a stop. Said clock is preferably not provided with a minute hand, and the dial itself is substituted for the usual hour hand. But a minute shaft 22 is included, upon which the hour stem is journaled. If desired a pointer 23, adapted to be manually set at any hour desired, may

be mounted upon said dial or hour stem and rotate therewith to show the hour at which the clock is set to open said gate, and at which the door should be unlocked. The 5 clock chamber on the dial side is preferably covered by a glass 24 mounted thereon in any suitable manner, as in a frame or lid 25 which may be hinged to the casing 1 at one side and may be locked at the opposite side as at 26 by any suitable latch or lock.

The winding stem may be extended to a point between said plates 18 and 17 and may be reached at a certain period through 15 an aperture 27 in said dial and plate 17. In equivalent manner the clock may be set from the dial side, by turning the minute shaft, to open the gate at the appointed hour. Said dial and supporting plate may 20 also be turned from the outside of the door by making a keyhole through said door through which the opposite end of the minute shaft may be reached. In the form shown, a suitable hair spring, balance wheel, 25 and escapement are deemed to be included as parts of the clock as will be well understood by those familiar with the art of clock structures, but are omitted from the drawings as well known details of structure 30 not essential to be particularly described or shown. In order to hold said bolt in retracted position during the day, said lock is provided with a manually operable hold back latch of any suitable construction, 35 adapted to engage a notched lug 2^a formed on and extending rearwardly from the retracted bolt. Said hold back latch preferably comprises a bar 28, adapted to be reciprocated in guides 29, a spring 30 is provided to actuate said bar in operative direction and any suitable means, as a bell 40 crank 31 and a push rod 32 is provided for retracting said bar, said push rod extends through the door and may be operated from 45 the outside thereof. Said reciprocatable bar has formed thereon a shoulder 28^a normally extending into the path of said lug 2^a and in operation adapted to engage the notch in 50 said lug. Said shoulder is beveled on the side toward said lug to correspond approximately with the beveled end of said lug. Said hold back latch, or slide stop, is preferably, as shown, adapted to be retracted from the outside of the door, but, if desired, 55 the same or a similar stop may be retracted instead, or in addition, from the inside of the door. The free end or nose of said bolt 2 is preferably beveled on both sides at its forward end.

60 Assuming the bolt to be retracted and said slide stop engaged, when it is desired to lock the door the manager or operator opens the glass cover and turns the dial so as to set the gate-lifting post 21 a predetermined 65 dial-time backward from its point of con-

tact with said gate finger, the termination of said time being the time intended for the opening of the gate. If for convenience a pointer hand is provided, he sets said pointer hand to point to the dial hour at which the 70 lock may be opened, as a reminder of the hour fixed. Thus assuming the post 21 to be positioned below the dial hour XXIV on a 24-hour dial, and that it is desired that ten hours shall elapse before the door can 75 be normally opened, the dial will be set so that said dial hour XXIV will be ten hours back from the gate and the dial figure at the gate should then be X. If the actual hour of setting the clock is then 9 P. M. or 80 the ninth dial hour, the actual time for opening the door ten hours later, would be 7 A. M. or the XIX dial hour to which hour the pointer should point,—that is, the gate lifting post and dial mark 24 will pass the 85 date at the 19th hour of a 24 hour period or at the 7th hour of a 12 hour period. The operator then goes out, closes the door and from the outside retracts said slide stop by 90 means of the push rod and bell crank, whereupon the springs on the rods 3 and 4 thrust said bolt into operative position and the gate falls. At the opening hour the gate is lifted for a short period, during which the person appointed to open the store must be 95 present to unlock the door or the gate will fall and he cannot unlock it without a special key, intended to be carried only by the manager for turning the dial from the outside. The lock of my invention herein 100 described is intended to be used in addition to a separate door lock in which the clock features are omitted. Assuming that the appointed clerk is present at the appointed time, he unlocks the door by first 105 unlocking the separate lock (not shown) and pushing the door open, the beveled nose of the lock bolt of my invention being forced back by the hasp, causing the rod 4 to extend under said gate and said marker to 110 mark said dial. At the same time the beveled end of the lug 2^a engages the beveled side of the shoulder 28^a and forces said shoulder out of its path, said shoulder being immediately returned by said spring 30 into 115 the notch of said lug 2^a, thus holding said bolt in retracted position.

Assuming that the clerk is not present at the time appointed for opening the lock, the gate falls again after the disengagement of the finger 19^a from the opening post 21 and the lock cannot then be opened without the use of a special dial-turning key adapted to be applied to the outer end of the minute shaft whereby the dial can be rapidly advanced to bring the gate-opening post 21 again into engagement with the finger 19^a to reopen said gate. If desired, the marker may be omitted. It is obvious that the structure of my invention may be modified 120

in various details within the spirit and scope of certain of my claims.

What I claim is—

1. The combination with a suitable case, of a spring actuated bolt adapted in operative position to extend therefrom; a clock mechanism including a minute shaft, an hour stem concentric with said shaft, means for driving said shaft and stem, a stationary plate, a plate mounted upon said hour stem concentrically therewith and adapted to rotate therewith, said rotatable plate being approximately parallel with said stationary plate and spaced therefrom; a rod 10 extending rearwardly from said bolt toward said clock mechanism and adapted to extend a short distance into the space between said two plates when said bolt is retracted; a gate positioned across the path of movement of said rod toward said space; a finger extending from said gate into said space; means carried by said rotatable plate and adapted at some time during the rotation of said plate to engage said finger and thereby 15 lift said gate; means for guiding said gate in a path eccentric to the path of said finger-engaging means, whereby said finger will be drawn out of engagement with said engaging means when said gate is lifted.
  2. The combination with a suitable case, of a reciprocable bolt adapted to extend therefrom in operative position; a clock mechanism including a minute shaft, an hour stem concentric therewith, means for 20 driving said minute shaft and hour stem, a plate mounted on said hour stem concentrically therewith and adapted to rotate 25
  - 30
  - 35
- therewith; a rod extending rearwardly from said bolt toward said clock mechanism said rod being adapted to extend at its free end a short distance across said rotatable plate approximately parallel therewith when said bolt is retracted; a gate positioned across the path of movement of said rod toward said clock mechanism; a finger extending from said gate a short distance across said plate approximately parallel therewith when said gate is in operative position; a post extending from said rotatable plate, said post being adapted at some time during the rotation of said plate to engage said finger and lift said gate; guides for directing the movement of said gate tangentially from said rotary plate while said gate is being lifted, whereby said finger is drawn out of engagement with said post when said gate is lifted to its maximum height; a dial formed on or secured to said rotary plate whereby the position of said post with respect to said gate may be determined; a second rod extending rearwardly from said bolt; a marker carried by said second rod at its free end, said marker being adapted to mark said dial near its periphery during the retraction of said bolt; means for operating said bolt; means for holding said bolt in retracted position, and means for releasing said holding means.

In testimony whereof, I hereunto affix my signature, in pressure of two witnesses.
